UNITED STATES PATENT OFFICE.

JOSHUA NUTTALL, OF ALLEGHENY, PENNSYLVANIA, ASSIGNOR TO HIMSELF
AND JOSHUA RHODES, OF SAME PLACE.

MACHINE FOR REDUCING AND STRAIGHTENING TUBES.

SPECIFICATION forming part of Letters Patent No. 236,245, dated January 4, 1881.

Application filed July 24, 1880. (No model.)

To all whom it may concern:

Be it known that I, JOSHUA NUTTALL, of Allegheny city, county of Allegheny, State of Pennsylvania, have invented or discovered a new and useful Improvement in Machines for Rounding, Straightening, and Sizing Tubes and Rods; and I do hereby declare the following to be a full, clear, concise, and exact description thereof, reference being had to the accompanying drawings, making a part of this specification, in which—like letters indicating like parts—

Figure 1 shows a side elevation of my improved machine for rounding, straightening, and sizing tubes, &c. Fig. 2 is a top plan view of the same, the driving-shafts and gearing being broken away. Fig. 3 shows an end elevation, and Fig. 4 is a detached view, of one pair of the rolls, and illustrative of the circumferential bearing taken by the rolls upon the tube, pipe, or rod.

My invention relates to a machine for rounding, straightening, and sizing tubes, rods, and similar articles; and it consists in the arrangement of a series of concave-faced rolls on two opposite sides of the line of feed of the article to be operated on, the rolls of each series being arranged in a common frame with their axes parallel, but crossing and inclined to the line of feed at other than a right angle, and the two opposite sets or series crossing such line in different directions; also, in means for mounting, driving, and adjusting such sets or series of rolls.

In certain branches of pipe or tube manufacture—as, for example, in making boiler-tubes—it is desirable and necessary to round, straighten, and size the same with great accuracy.

Machines of the class to which my present invention relates have heretofore been used successfully for rounding, straightening, and reducing solid bars; but when used on iron pipe or tubing they have but little effect in rounding or reducing the size unless the article is passed through the machine several times, which operation is attended with delay and expense. This imperfect rounding and reducing action is due in a great measure to the fact that in such machines the line of feed or bearing has been nearly in the direction of the length of the rolls, entering and leaving the rolls in a central line between the roll ends.

This arrangement gives the rolls a long straight bearing on the sides of the rod, which may be effectual in straightening a rod or tube; but if pressure is applied through the rolls for the purpose of reducing the size of a pipe or tube such pipe or tube is liable to yield or bulge out between the lines of bearing, thus distorting the article rather than reducing and rounding it; or, if this does not occur, the twisting or torsion force exerted in such machines is liable to rend and destroy the pipe or tube for use.

My invention is designed and adapted not only to straighten pipes and tubes, but also to reduce them to a uniform size and make them round; and, while it is especially designed for this class of work, it is also well adapted to produce the same effects on solid metallic rods.

My improved machine is constructed as follows: On suitable bed-pieces A are mounted two separate roll-frames, B B', consisting of end blocks, b, and upper and lower horizontal bars or bearings, b'. Within these frames are mounted a series of two, three, or more concave-faced rolls, C C', respectively, a like number being in each frame. These rolls C C' in the two frames are arranged in pairs opposite each other and on opposite sides of the pipe or tube D to be operated on. All the rolls in one frame, as B, are arranged with their axes parallel with each other and inclined forward across the side of the tube or the line of feed, while the rolls in the other frame, B', are also parallel to each other, but are inclined backward across the side of the tube, or in a different direction from the first set or series mentioned. As thus arranged the line of feed, as represented by the tube D, Fig. 1, is across the roll-faces from side to side, instead of from end to end; and the concavity of the roll-faces being adapted to the size of the tube to be operated on, the rolls will take not only a long bearing lengthwise on the pipe or tube, as heretofore, but they will also take such bearing in a spiral direction around the pipe or tube, and thereby they will, in effect, encircle a considerable part of its circumference. This circumferential bearing is represented or illustrated in detached view, Fig. 4. By providing several pairs of these rolls in immediate succession the tube is practically inclosed by them for a considerable length, and being subjected to their simultaneous action, the tube and rolls

rotating together, the tube is prevented from bulging or changing its form under compression of the rolls, and as a consequence it is reduced in size thereby, and also made round 5 and straight. Also, all the rolls in each side being carried on a single frame, the two sets can be adjusted with ease and accuracy to produce any desired reduction of the tube. This adjustment is effected by moving the 10 frames at either or both of their ends upon the bearings A, either toward or from each other, by means of bolts e passing through the ends of the frames, or by other known or suitable means. Also, to raise or lower the top bars 15 b' of the frames to adjust the roll-bearings, liners e' and bolts e² may be employed in the usual way.

The roll-necks are journaled on the upper and lower bars, b' b', of the frames in any suitable way; but to secure compactness and strength I notch the upper and lower edges of these bars, as at h h, giving them, in effect, a zigzag form, the parts on which the roll-journals are fixed being at right angles to the 25 axes of the respective rolls.

In order to drive the rolls in unison they may be geared either above or below the roll-frames. I have shown them geared above to shafts R by bevel-gearing r. The two sets or 30 series of rolls are driven in the same direction, and their rotation causes the tube or rod D to rotate, and the cross relationship of the opposite rolls gives the tube or rod a rapid forward feed along with its rotary movement. In 35 order to scale the tubes or rods, and thereby give them a smooth finish, tubular guides S may be secured to the ends of the frames B B' by slots and bolts s, thereby allowing of the adjustment of the frames as above described. The opening S' of the guides is in line of feed, 40 so that the tube or rod passes through it, and in such passage the rolls give the projecting end of the tube more or less vibration, thus striking it against the sides of S and knocking off the scale. These guides S also serve to 45 direct the tube or rod to the proper point in the rolls as it is first fed in.

I have found it more convenient and practical to provide different sets of rolls for different grades of work. Such different rolls, if nearly of the same size and length, may be used in one pair of frames B B', though, if they differ considerably in these respects, I prefer to provide separate frames for the different sizes. Such frames may be adjustably secured to the bed-pieces A, or equivalent supports, in any convenient way, as by bolts and slots, or by a dovetail-slide connection. 55

With this machine, having, as shown and 60 described, a plurality or series of rolls arranged in immediate succession on two opposite sides of the tube or line of feed, I am enabled with a single pass of a pipe or tube to accomplish better results with less expense and in less 65 time than can be secured by a number of passes on machines of this class heretofore used; and not only is this advantage secured

on pipes and tubes, but also my machine is well adapted for reducing, rounding, and straightening solid rods of iron or steel. 70

I am aware that two sets or pairs of crossing rolls have been arranged in line with a common line of feed, as described and shown in English Patent No. 1,510 of 1857, to W. Hale; but such separate sets or pairs have been mounted on 75 separate frames, and therefore cannot be adjusted with the facility and accuracy which are secured by my improvement. It is important, in order to secure the best results, especially upon light pipe, that the sets of rolls should be 80 in close succession, in order to prevent bending or distortion of the pipe between different sets of rolls caused by its rapid revolution and tendency to vibration. Also, when it is desired to reduce the tube in size, great accuracy of adjustment of the successive sets of rolls is required, especially when three or more such sets are used, as shown herein. These 85 requisites or advantages are fully secured in my improvement by mounting all the rolls 90 on each side of the line of feed parallel, in close succession, and in a common or single frame.

In patent granted to me July 1, 1879, No. 216,967, I have shown and described one set 95 or pair of crossing rolls having a line of feed in a direction lengthwise with the rolls and midway between the roll ends. Such construction and arrangement, however, does not contain my present invention for the reasons 100 hereinbefore set forth.

I claim herein as my invention—

1. In a machine for reducing, rounding, and straightening pipes, tubes, and rods, a plurality or series of rolls arranged in close succession in a common frame on one side of the line of feed, said rolls having their axes parallel and all crossing the line of feed at other than a right angle, in combination with a set or series of like number of rolls arranged in similar succession in a common frame on the opposite side of the line of feed, the latter set or series also crossing the line of feed, but in a different direction from the first set or series, substantially as set forth. 115

2. In a machine for reducing, rounding, and straightening pipes, tubes, and similar articles, the combination of a series of rolls, C, arranged in a common frame, B, on one side of the line of feed, with a similar series of rolls, C', arranged in a common frame, B', on the opposite side of the line of feed, and mechanism for adjusting either or both ends of such frames toward and from each other, substantially as described, whereby the two sets or series of 120 rolls can be adjusted to produce the desired amount of reduction in one pass of the tube or rod. 125

In testimony whereof I have hereunto set my hand.

JOSHUA NUTTALL.
